UNITED STATES PATENT OFFICE.

FRANCIS BEAUFORT COCKBURN, OF CINCINNATI, OHIO, ASSIGNOR TO THE LODGE & SHIPLEY MACHINE TOOL COMPANY, OF CINCINNATI, OHIO, A CORPORATION OF OHIO.

APRON DISK TRANSMISSION MECHANISM.

Application filed February 21, 1924. Serial No. 694,219.

To all whom it may concern:

Be it known that I, FRANCIS B. COCKBURN, a subject of Great Britain, and residing at Cincinnati, in the county of Hamilton and State of Ohio, have invented a new and useful Apron Disk Transmission Mechanism, of which the following specification is a full disclosure.

This invention relates generally to lathes and is particularly directed to improvements in mechanism for operating alternately the carriage feed on the bed or the tool slide cross feed on the carriage, preferably by a common or single actuator, although its embodiment is perceptible for transmission mechanism in general and the control thereof.

Objects of the invention are to provide means operable by a single actuator for selectively controlling the cross or longitudinal feeds, and thereby positively preventing simultaneous operation of both feeds.

Another object is to provide a friction device for transmitting power for cross and longitudinal feeds, which device is adjustable to permit slippage in case of accident, as is desirable in case of overload.

Another object is to obtain selective operation of the alternately operable friction devices, by means of a hand lever instead of a revolving knob, the hand lever being a more positively operable and more easily actuatable device.

Another object is to provide for an application of pressure to the friction devices independently of the operator, in such manner that a minimum effort only will be required by him to transmittingly connect respective mechanisms with the power, the pressure applying devices being designed to obtain the desired clamping pressure, but sufficiently yieldable under undue machine strains to permit slippage of the transmission connections, thus acting as safety devices.

Another object is to provide for the yieldable locking of the operating lever at limits of movement in each direction.

Although the device illustrated and described herein is shown applied to a lathe, it is understood that the same may be used for other purposes wherein it is desired to selectively control two mechanisms which are to be alternately transmittingly coupled,

and which must be positively prevented from simultaneous operation.

Other objects and certain advantages will appear in the description and drawings forming part of this specification, in which drawings:

Figure 1 is a front elevation of a portion of a lathe apron provided with my improved mechanism, the parts being broken away to more distinctly show the construction.

Figure 2 is a vertical cross section on line 2—2, of Fig. 1, the mechanism being shown in neutral position.

Figure 3 is a detail elevation of the operating lever and adjacent parts.

Figure 4 is a detail vertical section on line 4—4, of Fig. 3, through the operating lever and compressing and decompressing mechanism for the clutch activating expansion elements.

Figure 5 is a top plan view with the top plate of the apron removed to more clearly show the relation of the clutch to the transmission mechanisms.

The invention is primarily disclosed as a part of the transmission mechanism carried by the carriage apron of a lathe for alternately feeding or translating the carriage upon the lathe bed or the tool slide in a cross feed on the carriage. In its fullest capacity it may be referred to as friction clutching or transmission controlling mechanism compactly arranged comprising a driving member adapted to be alternately frictionally engaged or connected with the plurality of driven members. The driven members are disposed at opposite sides of the driving members, with friction disks disposed respectively between, each of the driven members and driving members, and compressively frictionally engaged by separate springs as interposed respectively between the driven members and driving members, in an arrangement whereby the springs may be controlled to impart their pressure opposingly against the driving and driven members to be frictionally engaged. The springs are relatively arranged to adapt the same to be controlled by a single lever or actuator whereby the springs will exert a pressure opposingly against the actuator for neutralizing the actuator and clutching mechanism, and also adapting the actuator to be centralized for controlling the pressure

of both springs for alternate clutch control.

Referring to the drawings, 1 designates the base or bed of an ordinary lathe, 2 the apron rack attached at the outside of and beneath an overhanging portion of the bed, said rack being adapted for engagement by one element of the apron translating mechanism, for feeding the carriage upon the rails of the lathe bed. The numeral 3 designates 10 the feed or power shaft, and 4 the apron proper suitably gibbed to the rail 5 in a manner not herein shown. Inasmuch as the invention relates particularly to clutch means for alternately transmittingly connecting power with the carriage feed or tool slide cross feed on the carriage, and for shifting power alternately from one to the other, and also to means for preventing simultaneous operation of both mechanisms, 15 and inasmuch as virtually all mechanisms herein are mounted and movable with the carriage and apron thereof, it is believed unnecessary to further illustrate the structure of the lathe proper.

20 The apron is loosely traversed by the feed shaft 3 and said apron is guided upon the lathe bed and moves translatively with reference to the screw and bed in a well known manner. Splined to the lead or power shaft 30 3 are the sleeved bevel gears 5, 6, each shiftable by suitable mechanism for alternate engagement with the driving bevel gear 7 keyed to a cross shaft 8 rotatively journaled in the apron 4. Attached to the cross shaft 35 8, in this instance as an integral part thereof, is a spur gear 9 in mesh with peripheral teeth 10 of a rotatable preferably constantly driven and shiftable clutch member 11, attached to and rotatable with a hub extension 12 journaled, as more fully herebelow described, for rotation and translation in the apron. Journaled rotatably in a suitable bearing in the apron by means of a tubular hub extension 15, is a clutch member 40 45 20 substantially similar to clutch member 11, and having peripheral spur teeth 21 and interior teeth 22, with which interior teeth are non-rotatably engaged friction clutch disks or members 23 disposed at the interior of the 50 member 20.

The hub extension 15 surrounds and is rotatable upon the shiftable hub extension 12 of the clutch member 11, which extension 12 forms a support and bearing for the member 55 20. The teeth 21 are in mesh in this instance with an idler gear 25 rotatably mounted upon the upper overhanging portion 26 of the apron bed engaging part, upon which part is mounted in the usual manner the 60 cross slide not herein shown. A cross slide feed shaft is indicated at 27 and the same has at its outer end a gear 26 meshing with the gear 25. The gear teeth 21 and gears 25 and 28 constitute transmission means connecting the cross feed driving clutch mem-

ber 20 with the cross slide feed shaft. Any other equivalent slide feed means may, however, be used to connect the clutch member 20 with the cross slide feed shaft. It will be understood that when the feed shaft 26 is 70 rotated the cross slide will be correspondingly translated.

As before stated, the tubular extension 15 of the member 20 has translatable and rotatably journaled therein the tubular extension 12 of the shiftable driving clutch member 11, which member has interior teeth 13 having clutch disks 14 non-rotatably engaged therewith in a manner similar to that of the clutch member 20. Rotatable within 80 the tubular extension 12, as a bearing, is a shaft 40 to which is keyed a clutch member 41 having peripheral teeth 42, with which teeth are non-rotatably engaged friction disks 43 alternately interposed between the 85 disks 14 of the clutch member 11. The teeth 42 are in this instance formed upon an annulus 55 attached by screws 56 and pin 57 to the clutch member 41. The cross feed driving clutch member 41 is keyed to the shaft 90 40 and abuts a gear 45 thereon, which gear is in mesh with a spur gear 46 (see Fig. 5) mounted upon a shaft 47 journaled crosswise in the apron, the cross shaft 47 carrying at its inner end a spur gear 48 in mesh or 95 adapted to be in mesh with the rack 2. The shaft 40, gears 45, 46, shaft 47 and gear 48 herein constitute for convenience of description, means transmittingly connecting the rack 2 with the apron feed driving clutch member 41. The shaft 40, however, may be separately considered as a part of the clutch mechanism proper, and for this reason said shaft is also herein designated as an apron translating drive shaft, and the gear 45 100 upon this shaft could be transmittingly engaged with the rack 2. The shaft 40 is extended beyond the sleeve 12 at the outer end and beyond the gear 45 at the opposite end, and is thus journaled at opposite sides of the 105 clutch member 41, respectively, in the sleeve 12 and in a bearing 49 of the apron.

The clutch member 11 as a separate piece is in this instance attached to the hub 35 by a suitable fastening device 50, the hub 35 110 having formed on its periphery teeth 51 with which are non-rotatably engaged disks 52 alternately disposed between the friction disks 23 of the clutch member 20. The shiftable driving clutch member 11 having the hub 35 and tubular extension 12 is thus disposed intermediate the members 20, 41, and is adapted when shifted to alternately frictionally unite the clutch disks 43, 52, and 120 14, 43. The shiftable member is also normally adapted to lie in neutral or unclutched position between the members 20, 41, and means is herein provided for positioning and holding the disks of the clutch member, as well as the member itself in neutral posi- 125 130

tion with the disks positively disengaged from the disks of the other clutch members, at opposite sides thereof.

The tubular hub extension 12 at its outer end is provided with an adjustable annular abutment 60, which in this instance has threaded engagement with the counterturned portion of said extension, and said abutment is held by a screw 61 against accidental displacement.

Resilient or expandable elements 65, 66, are arranged at relatively opposite sides of and are alternately engageable with said abutment, the said elements, herein shown as 15 coiled springs, being mounted in the following manner: The element 65 surrounds the outer end of the shaft 40, is spaced therefrom and abuts the washers 67, 68. The washer 67 engages a counterturned portion 20 of the abutment which counterturned portion forms a shoulder, and the washer, in a neutral position of the member 11, is disengaged and slightly spaced away from the abutment. The outer face of a cupped 25 washer 68 abuts a cap 70 having threaded engagement with a forwardly disposed tubular extension 71 of the apron 4, and said washer also surrounds and is engaged with the shaft 40, a nut 72 being engaged with 30 the outer end of the shaft 40 for holding the washer 68 against displacement when the cap 70 is removed. The spring 66 at one end abuts the washer 75, which washer is normally spaced from the abutment in a 35 manner similar to washer 67. The means for holding the washers 67 and 75 thus spaced away from the abutment, herein comprises translatable diametrically related lugs interposed between the washers as herebelow 40 more fully described, the said lugs acting in conjunction with lever controlled operating means to compress and decompress the expansion elements. The spring 66 at its opposite end abuts a washer 76 which washer 45 in turn is engaged with the outer end of the tubular extension 15, which extension projects slightly beyond a bearing bushing 80 held by a pin 81 against rotation in the front wall of the apron. The resilient elements, 50 herein shown as springs, are assembled under compression and are thereafter normally under equal compression, as shown in Fig. 2. When either spring is compressed the other engages the abutment and causes trans- 55 lation of the member 11 in appropriate direction to cause clutching engagement thereof with one or the other of the cooperable clutch members 11, 20, a maximum pressure being exerted by the expansion mem- 60 bers upon the clutch disks and such pressure being sufficient to drive the largest cut that the machine is capable of carrying, but not sufficiently great to prevent slippage of the disks should undue strain be brought to bear 65 upon the machine.

It will also be seen as hereinafter more fully set forth, that the degree of pressure exerted upon the cooperative friction disks is not dependent upon the effort of the operator but is obtained by simple easy movement of the lever, through the intermediary of the expansive force of the springs. The lever is, moreover, automatically locked at limits of movement in each direction so that after a given clutch is thrown in the mechanism will remain so set until the lever is again operated.

The expandable elements 65, 66 (as shown in Fig. 2) act counter to one another, and means is provided for compressing either 80 element while simultaneously decompressing the other, whereby the elements are alternately activated to engage the abutment 60 and correspondingly move the shiftable member 11 for alternate clutch engagement 85 of its friction members or disks with the cooperable friction members or disks of the members 20, 41.

Means is interposed between the washers 67, 75, for holding the same normally disengaged from the abutment, to permit a degree of free translation of the shiftable member 11, in neutral position, and also to provide for alternately activating the springs, which means consists of lugs 85 relatively diamet- 90 rically disposed and integral with a cylindrical shaft 86 rotatable in suitable bearings, in this instance a bore of the extension 71, said shaft being centrally cut away to provide a forked structure having arms 87 95 from which horizontally project the pins or lugs 85. The shaft 86 has a square projection 89 engaged in a corresponding socket 90 of an actuating arm 91 and said arm is removably non-rotatably attached by a screw 100 88. The arm extends downwardly and has a notch in its lower edge. The notch has inclined portions 92 relatively upwardly convergently related, the said surfaces merging into straight parallel portions 93 at 110 right angles to the end wall 94 of the notch. (See Fig. 2). The various surfaces just described coact with a rotatable cam 95, to shift the arm 91, and to lock the same at limits of shifting movement in each direction. To accomplish the locking operation above mentioned the rotatable cam 95 is provided with relatively oppositely inclined surfaces 100 converging upwardly in a direction generally the same as the surfaces 91, 120 but of different relative angularity, and in the neutral position of the cam the said cam has a knife edge engagement as at 101 with the surfaces 92. (See Fig. 2).

The cam 95 is formed as a projection integral with and upon one end of a cross shaft 105 rotatably journaled in ears 106 extending outwardly from the front wall of the apron. Between the ears is disposed and keyed to the shaft, a clutch operating 130

- lever 107 actuatable for disposing the clutch mechanism respectively in neutral position, and in clutching positions at opposite sides of the neutral position. When the lever is shifted to the right, as viewed in Fig. 2, the projections 85 compress the spring 65 and activate the spring 66, which when expanding shifts the member 11 for clutch engagement with the cooperable member 20.
- 10 When the lever is shifted to the left, the projections 85 compress the spring 66 and activate the spring 65, the expansible force of which translates the member 11 in the opposite direction for clutch engagement with the member 41. When the lever is positioned as at *a* (see Fig. 3) the arm 91 is positioned as shown in dot-and-dash lines and the surface 100 of the cam is engaged flatly against the end wall 94 of the slot.
- 15 The surface 93 is simultaneously engaged with the curved portion of the cam as shown and both arm 90 and lever 107 are thus locked against accidental displacement. Reverse locking action takes place when the lever is shifted to position *b* shown in Fig. 2.

By the above described mechanisms means is provided for engaging and disengaging either the longitudinal or the cross feed by a single operating means, and the power for feed is transmitted through a friction member which may slip in case of overload of the machine. Moreover, the pressure exerted on the friction disks is independent of the effort of the operator but is at the same time great enough to drive without slipping, the largest cut of which the machine is capable. The length of the arm 91 is so proportioned that the lever 107 may be moved to its various positions with great ease and in the limit positions the lever is yieldably locked against accidental displacement. The device also provides against simultaneous operation of both longitudinal and cross feeds and this provides what may be termed an interlock between the mechanisms as well as between respective clutches therefor.

The mechanism above described for alternately transmittingly connecting the cross slide and apron feed with the power can be utilized under other similar conditions where it is desirable or necessary to alternately connect a plurality of mechanisms, which are designed for independent operation, and which should not be simultaneously operated.

Having described my invention, what I claim is:

1. In a device of the class described, a rotatable and shiftable clutch member having an abutment thereon, cooperable clutch members at relatively opposite sides of said shiftable clutch member alternately engageable by said member for movement in unison therewith, expansible elements at relatively

opposite sides of and engageable with said abutment, said elements acting counter to one another, and means for compressing either element while simultaneously decompressing the other, whereby said elements are alternately activated to engage said abutment and correspondingly move said shiftable clutch member, for alternate clutch engagement with said cooperable clutch members.

2. In a device of the class described, a rotatable and shiftable clutch member having an abutment thereon, cooperable clutch members at relatively opposite sides of said shiftable clutch member alternately engageable by said member for movement in unison therewith, expansible elements at relatively opposite sides of and engageable with said abutment, said elements acting counter to one another, and means for activating either element while simultaneously deactivating the other, whereby said elements are alternately activated to engage said abutment and correspondingly move said shiftable clutch member, for alternate clutch engagement with said cooperable clutch members.

3. In a lathe, a power shaft, an apron having apron translating mechanism, a cross slide feed shaft, a shiftable clutch member having an abutment thereon, transmission mechanism connecting said clutch member and power shaft, cooperable clutch members at opposite sides of said shiftable member alternately engageable thereby, transmission means respectively connecting said apron translating mechanism with one of said cooperative clutch members and said cross slide feed shaft with the other cooperative clutch member, expansible elements at relatively opposite sides of and engageable with the abutment of said shiftable clutch member, said elements acting counter to one another, means for compressing either element while simultaneously decompressing the other, whereby said members are alternately activated to engage said abutment and correspondingly shift said shiftable clutch member for alternate clutch engagement with said cooperative clutch member to correspondingly activate either the apron or cross feed transmission mechanisms and prevent simultaneous operation of both mechanisms.

4. In a device of the class described, a rotatable and shiftable driving clutch member having an abutment thereon, cooperable driven clutch members at relatively opposite sides of said shiftable clutch member alternately engageable by said member for movement in unison therewith, expansible elements at relatively opposite sides of and engageable with said abutment, said elements acting counter to one another, means interposed between and engaging said expansible elements for holding the same disengaged from said abutment to obtain and

maintain positive disengagement of said shiftable member relative to said driven members, said means operable for compressing either element while simultaneously de-
5 compressing the other, whereby said elements are alternately activated to engage said abutment and correspondingly move said shiftable clutch member for alternate clutch engagement with said driven clutch
10 member.

5. In a device of the class described, a rotatable and shiftable driving clutch member having an abutment thereon, cooperable driven clutch members at relatively opposite sides of said shiftable clutch member alternately engageable by said shiftable clutch member for movement in unison therewith, resilient elements at relatively opposite sides of and engageable with said abutment, said 15 elements acting in opposition to one another, means interposed between and engaging said resilient elements for holding the same disengaged from said abutment to obtain and maintain positive disengagement of said 20 shiftable member relative to said driven members, said means operable for activating either resilient element while simultaneously deactivating the other, whereby said elements are alternately activated to engage said abutment and correspondingly move said shiftable clutch member for alternate clutch engagement with said driven clutch member.
25

6. In a device of the class described, a shiftable clutch member having an abutment thereon, cooperable clutch members at relatively opposite sides of said shiftable member alternately engageable by said shiftable member for movement in unison therewith, resilient elements at relatively opposite sides of and engageable with said abutment, said 30 elements acting counter to one another, element activating means interposed between and engaging said elements for normally holding the same disengaged from said abutment to obtain and maintain positive disengagement of said shiftable member relative to said driven members, said means operable for activating either element while simultaneously deactivating the other, and means for locking said element operating means at opposite limits of movement, whereby said elements are alternately activated to engage said abutment and correspondingly move said shiftable clutch member for alternate clutch engagement with said cooperable clutch member, and whereby said clutch engagement may be maintained.
35

7. In a lathe, an apron having apron translating mechanism, a rotatable clutch and driving member having a tubular extension journaled in said apron, a translatable driving and clutch member having a tubular extension journaled within the hub extension of said rotatable clutch member, said

tubular hub extension having an abutment thereon, an apron translating drive shaft rotatable within the tubular extension of said translatable clutch member and extending therebeyond and having a clutch member keyed thereto on the side opposite to that of the first mentioned clutch member, transmission mechanism respectively connecting said apron translating mechanism with said keyed clutch member, and said 75 cross slide feed shaft with said first mentioned clutch member, said cooperable clutch members alternately engageable by said shiftable member for movement in unison therewith, resilient elements at relatively 80 opposite sides of and engageable with said abutment, said elements acting counter to one another, and means for activating either element while simultaneously deactivating the other, whereby said members are alternately activated to engage said abutment and correspondingly shift said shiftable clutch member for alternate engagement with said cooperable clutch member to activate either the cross feed or transmission 85 mechanism and prevent simultaneous operation of both mechanisms.
90

8. In a device of the class described, a driven shaft, a sleeve surrounding and slideable and rotatable thereon, a support for said sleeve, an abutment upon said sleeve, and expansion members normally engaging said abutment at relatively opposite sides thereof, whereby when said abutment is moved in either direction one of said compression members is further compressed to allow clutch-actuating expansion of the other.
100

9. In a device of the class described, a driven shaft, a sleeve surrounding and slideable and rotatable thereon, a support for said sleeve, an abutment upon said sleeve, and expansion members normally expansively engaging said abutment at relatively opposite sides, whereby when said abutment is moved in either direction one of said compression members is further compressed and the other released for sleeve translation.
105

10. In a device of the class described, a driven shaft having a clutch member mounted thereon, a sleeve surrounding and slideable upon said shaft, said sleeve having clutch members, a rotatable member having clutch members, an abutment upon said sleeve, and expansion members normally engaged under compression against opposite sides of said abutment, whereby when said abutment is moved in either direction one of said expansion members is further compressed, the other expanded, and released to move said sleeve, into clutch engaging position.
115

11. In a device of the class described, a driven shaft having clutch disks mounted thereon, a sleeve surrounding and slideable

and rotatable upon said shaft having clutch disks thereon, a third member having clutch disks thereon rotatable upon said sleeve, a support for said sleeve, an abutment upon said sleeve, and compression members normally expansively engaging said abutment at relatively opposite sides, whereby when said abutment is moved in either direction one of said compression members is further compressed, the other expanded, and the sleeve and disk moved in opposite directions for alternately compressively engaging the disks at opposite sides thereof.

12. In a device of the class described, a bed, an apron slideable thereon, mechanism for feeding the carriage of the bed, mechanism for feeding the slide on the carriage, an alternative double-friction clutch mechanism for selectively operating the carriage or slide feeds, a single clutch actuator therefor having an abutment thereon, expansible members at relatively opposite sides of said abutment, each under compression, whereby when said actuator is moved in either direction one of said expansible members is further compressed to permit expansion of the other, for transmittingly connecting one of said feeds, and whereby said actuator is held in initial position by equal pressure applied in relatively opposite directions.

13. In a device of the class described, a bed, a carriage and tool slide, a driving shaft on the bed, constantly intermeshing gear mechanism on the carriage operated by said shaft, mechanism for feeding the carriage on the bed including clutch members, mechanism for feeding the slide on the carriage including clutch members, and means for selectively connecting and disconnecting said carriage gear mechanism alternately with said carriage or slide feed mechanism, which means comprises a shiftable clutch member alternately cooperable with corresponding clutch members of either carriage or slide feed mechanisms, an abutment on said shiftable clutch member, and compression members compressively engaging said abutment at relatively opposite sides whereby when said abutment is moved in either direction one of said compression members is further compressed and the other ex-

panded to bring said shiftable member into transmission engagement with the corresponding clutch disks.

14. A device of the class described, comprising three transmission members adjacently disposed having their axes concentrically engaged, and of relatively different lengths with their ends arranged to provide shoulders opposingly with respect to the intermediate member, friction disks respectively interposed between said members, the intermediate member movable in opposite directions for alternately frictionally engaging said respective members in pairs, springs under tension interposed between the end shoulders of the axes of said members for neutralizing the intermediate member, and means for moving the intermediate member to compressively bring the same into frictional engagement with one of said other members.

15. A device of the class described, comprising three transmission members adjacently disposed having their axes concentrically engaged, friction disks respectively interposed between said members, the intermediate member movable in opposite directions for alternately frictionally engaging said respective members in pairs, springs under tension interposed between the ends of the axes of said members and relatively opposing the end of the axis of the intermediate member for neutralizing the same, and means for moving the intermediate member to compressively bring the same into frictional engagement with one of said other members.

16. In a device of the class described, a driven shaft having a clutch member mounted thereon, a sleeve surrounding and slideable upon said shaft, said sleeve having clutch members, a rotatable member having clutch members, an abutment upon said sleeve, means for selectively shifting the abutment, and means in connection with said shiftable abutment for causing operation of said clutch members, corresponding to the direction of abutment shift.

In witness whereof, I hereunto subscribe my name.

FRANCIS BEAUFORT COCKBURN.
